UNITED STATES PATENT OFFICE.

PRINCE B. BREEDEN, OF NORFOLK, VIRGINIA.

WHIP.

1,099,013.

Specification of Letters Patent.

Patented June 2, 1914.

Application filed January 10, 1913. Serial No. 741,348.

To all whom it may concern:

Be it known that I, PRINCE B. BREEDEN, a citizen of the United States, residing at Norfolk, in the county of Norfolk and State 5 of Virginia, have invented new and useful Improvements in Whips, of which the following is a specification.

This invention relates to horsewhips, and one of its objects is to provide a double whip 10 and a handle adapted to receive and inclose one of the whip members, whereby either one of said whip members may be disposed in position for use while the other is confined and held in the hollow handle.

15 A further object of the invention is to provide a whip of this character which will permit of the use of two whips of different sizes or kinds, which, in the event that one whip member is dispensed with, will permit 20 the other whip member to be inclosed within the handle for convenience in storage or transit, and which is provided with simple and effective means for securing the whip member or members to the handle.

25 The invention consists of the features of construction, combination and arrangement of parts hereinafter fully described and claimed, reference being had to the accompanying drawing, in which:—

30 Figure 1 is a sectional elevation of a whip embodying my invention, the whip handle appearing in longitudinal section. Fig. 2 is an enlarged detail section through the outer end of the whip handle and the coupling sleeve.

35 Referring to the drawing, 1 designates the hollow handle of the whip, which is closed at its outer end and open at its inner end, the said open inner end of the handle being 40 internally threaded to receive either one of the externally and oppositely threaded end portions 2 and 3 of a coupling sleeve 4. As shown, the end of the sleeves form sockets of different diameters to receive the correspondingly-sized tenons or butts of a pair 45 of whip staves or members 5 and 6 which are adapted to be fitted therein. Fig. 1 shows a whip provided with a pair of such reversible whip staves or members, one of 50 which, as the member 5, is inclosed in the handle, while the other, the member 6, projects outward for use. It is obvious that the 55 whip members may be reversed, so as to inclose the member 6 within the handle and dispose the member 5 for use, so that in the

event of the breakage of one whip member, a new one may be conveniently substituted therefor in an obvious manner. It will also be seen that this construction enables a pair of whip members of different sizes or kinds, 60 such as rigid and flexible whip members, to be used in connection with the same handle, and also permits of the substitution of new whip staves or members whenever the whip staff or staves in use are worn out or injured. 65

While the construction shown is designed for the use of a pair of whip staves in connection with a single handle, it will, of course, be understood that but a single whip staff need be employed, which, when the 70 whip is not in use, may be stored within the handle for convenience in packing and transporting the whip as a whole.

From the foregoing description, taken in connection with the drawing, the construction and mode of use of my improved whip 75 will be readily understood, and it will be seen that a device of this character is provided which embodies substantial advantages, and which may be made as ornamental 80 as desired.

It will also be seen that by reversely threading the coupling sleeve 4, and providing sockets of different diameters in the opposite ends thereof, the operator may readily 85 determine which end of the coupling member is in position to receive a certain kind or size of whip without confusion, the sockets also serving as gages by which whips of different kinds or sizes designed for use 90 in connection with a particular handle may be easily and conveniently selected from a large stock. It will further be seen that by providing the reversible coupling member with sockets of different sizes, whips of 95 relatively different degrees of flexibility, as for riding and driving, may be used in connection with one and the same handle, and that different styles of whips for the use of 100 dog and horse fanciers may also be employed in connection with a single handle.

I claim:—

As a new and improved article of manufacture, a whip comprising a hollow handle closed at one end and open and internally 105 threaded at its opposite end, a reversible coupling member provided with reverse external threads on opposite sides of its transverse center for interchangeable engagement with the threaded end of the handle, said 110

coupling member being provided with a continuous bore forming sockets of different diameters at its opposite ends, said sockets being coextensive in length with the reversely threaded end portions of said coupling member, and a pair of reversible and interchangeable whip staves having tenons of diameters to fit within the respective sockets, whereby either staff may be held projected

for use and the other stored in the hollow handle.

In testimony whereof I affix my signature in presence of two witnesses.

PRINCE B. BREEDEN.
